WALL PAPER.

No. 20,223.

Patented Oct. 21, 1890.

UNITED STATES PATENT OFFICE.

CHARLES BOOZE, OF BUFFALO, NEW YORK, ASSIGNOR TO M. H. BIRGE.
& SONS, OF SAME PLACE.

DESIGN FOR WALL-PAPER.

SPECIFICATION forming part of Design No. 20,223, dated October 21, 1890.

Application filed September 27, 1890. Serial No. 366,376. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying photograph, forming part thereof.

10 The leading feature of my design consists of two continuous intertwining vines of leaves and flowers of the rose arranged in horizontal wavy lines and crossing each other at uniform distances apart, forming an oval panel, 15 with a border composed of light bands disconnected at irregular intervals and arranged horizontally above and below the wavy vines of leaves and flowers, as represented in the

accompanying photograph. The disconnected ends of the light band are provided with 20 scroll-shaped ornaments, and narrow light lines are arranged parallel with and above and below the border.

My design is more particularly intended and designed to be used as a ceiling decoration or border.

What I claim is—

The design for wall-paper herein shown and described.

Witness my hand this 13th day of September, 1890.

CHARLES BOOZE.
